(57) **ABSTRACT**

A method and apparatus are provided for changing the unwinding direction of wound laps supplied by a delivery station in order to form a group of wound laps in which the face sides of adjacent wound laps are provided with the same distance and the longitudinal axes of the wound laps are disposed in one line. A rotatable vertical shaft is provided with one or more horizontal receivers that receive the laps sequentially and rotate each lap by 90° with the division of a winding group being maintained.

ROTATING STATION FOR WOUND LAPS

This application is a Division of Ser. No. 09/831,202, filed Jul. 18, 2001.

The invention relates to a method for delivery wound laps to a transport system.

As is known, wound laps (e.g. lap rolls) that are produced in a preparatory machine are produced by winding a web on an empty bobbin and are then ejected from the preparatory machine by breaking the web.

In order to supply the preparatory machine with textile material (e.g. silvers), several rows of textile material in cans are provided to the feed table of the preparatory machine. These cans are filled by draw frames which are provided upstream of the preparatory machines and thereafter moved by way of conveying systems or by hand to the feed table of the preparatory machine.

In order to keep the paths of transport small and to thus minimize the time applied for the transport of the cans, the preparatory machine, or its feed table respectively, must be associated with the can parking places in accordance with the upstream machines (draw frames).

In order to transfer the wound laps which are produced in the preparatory machine in a group via a transport system to downstream combing machines, the wound laps ejected by the preparatory machine are received by a conveying device and compiled step by step into a group of wound laps, with adjacent wound laps being disposed at a similar distance from one another. Such a device is shown for example in JP-52-25 125, with the wound laps supplied by the preparatory machine being discharged transversally to the delivery place via a conveyor belt and being compiled into a group of wound laps. This group is then transferred by means of a conveying system which is guided on a craneway to the respective combing machine. A similar device is disclosed in DE-197 20 545.3.

In the aforementioned embodiments, the group of wound laps that is compiled in the preparatory machine is received by a transport system and deposited close to the respective combing machine, with the ends of the wound web being aligned in such a way that the wound laps are provided in the desired unwinding direction.

In order to adapt the flow of material within the spinning mill according to the local conditions, it may occur that the adjacent row of combing machines is disposed offset by 90° or 180° to the provided group of wound laps with respect to the aforementioned embodiments. In this case, the end of the wound lap would face in the wrong direction following the transfer of the wound lap in the aforementioned manner and the wound lap would be present offset by 90°. This means that the unwinding direction of the wound laps placed on the combing machine would be facing opposite to the desired unwinding direction and the wound laps would therefore not be present in the desired unwinding direction.

In this case, it is necessary to turn the wound laps in a plane of its middle axis in order to obtain the desired unwinding direction.

An apparatus is known from JP-54-8184, with the wound lap which is ejected by the preparatory machine being transferred to a trough plate which cooperates with a rotating and lifting device. In this device, the trough plate is made to rotate by means of an angular gear, with a lifting movement being produced simultaneously with the help of a crank guide. As soon as the wound lap has been twisted (which in this case is 90° in the horizontal direction), the lap can be received by the grasping arms of a conveying system.

2

However, the arrangement shown is highly complex and is not suitable to form a group of wound laps with respectively aligned lap ends.

5 A device is known from EP-A2-406 923, with an apparatus being provided in order to change the orientation of thread packages. This device is also highly complex and not provided or suitable to produce an even group of wound laps. However, the arrangement shown is highly complex and is not suitable to form a group of wound laps with 10 respectively aligned lap ends.

15 A device is known from EP-A2-406 923, with an apparatus being provided in order to change the orientation of thread packages. This device is also highly complex and not provided or suitable to produce an even group of wound laps.

20 Accordingly, it is an object of the invention to provide a method and an apparatus which allows the orientation of the lap ends to be changed after delivery from a preparatory machine, with the subsequent formation of a regular group of wound laps for transfer to a downstream conveying system being ensured.

25 Briefly, the invention provides a method wherein the wound laps which are supplied by a delivery station are turned by 90° in a plane in which the longitudinal axis of the wound lap is disposed and with the laps being displaced thereafter step-by-step in the direction of their longitudinal axes.

30 The invention also provides an apparatus that is employed with a preparatory machine for sequentially delivering wound laps and a conveyor belt that is disposed transversely of the preparatory machine for sequentially receiving the delivered wound laps. Each wound lap has a tube disposed on a longitudinal axis of the wound lap.

35 The apparatus includes a first means for driving the conveyor belt in stepwise manner and a second means located between the preparatory machine and the conveyor belt for sequentially rotating each wound lap 90° in a plane of the longitudinal axis thereof and conveying each wound lap from the preparatory machine onto the conveyor belt in 40 coaxially equi-spaced apart relation.

45 The means for rotating the wound laps includes a vertically disposed rotatable shaft, at least one horizontally disposed receiver mounted on the shaft to engage within the tube of a wound lap and a drive for rotating the shaft to rotate an engaged lap on the receiver 90°. Each of the wound laps supplied by the preparatory machine and delivered by way 50 of the receiver is rotated by 90° in a plane in which the longitudinal axis of the wound lap is disposed and the wound laps are thereafter displaced from the zone of the receiver in the direction of their longitudinal axis. This allows changing the orientation of the unwinding direction by maintaining the horizontal direction of conveyance for the formation of the group of wound laps. Moreover, the horizontal direction of conveyance can be used simultaneously to slide the 55 wound laps directly on to the receiver.

60 In order to protect the outermost layer of the wound lap, the wound laps may be moved before and after the rotating process transversally to their longitudinal axes. This means that the wound laps are lifted off of the receiver prior to the rotating process and thereafter inserted again.

65 The means for driving the conveyor belt uses a controlled drive. This ensures that on the one hand there are no collisions during the transport of the wound laps and on the other hand an exactly aligned group of wound laps is provided for transfer to a conveying system.

It is preferably proposed to provide the rotating apparatus with a lifting device.

In order to maintain the lateral distances between the wound laps in the group of wound laps, it is proposed that the smallest distance between the rotational shaft of the apparatus and the face side of the wound lap pushed completely onto the receiver corresponds to half the distance between the face sides of adjacent wound laps within the group.

In order to ensure the positioning of the wound lap during the rotating movement, the receiver is provided at least partly with a non-slip cover.

In the embodiment where the wound laps are rotated 90°, the downstream combing machines can be arranged in their longitudinal direction parallel to the direction of ejection of the preparatory machine, which in a number of cases is very advantageous for the downstream flow of material.

It is further proposed that the apparatus be provided with at least four receivers that project outwardly from the rotational shaft, with at least two of the receivers being disposed in one line. It is possible with the cross-shaped arrangement of the receivers to rotate the rotational shaft of the apparatus in only one rotational direction, thus enabling a substantial simplification of the rotational drive. It is thus no longer necessary to perform a reversing movement in order to again receive a subsequent wound lap provided by the preparatory machine.

Further advantages of the invention are explained in closer detail in the following detailed description taken in conjunction with the accompanying drawings wherein:

FIG. 1 shows a schematic top view of a combing section of a spinning mill.

FIG. 2 shows an enlarged side view X according to FIG. 1.

FIG. 3 shows a side view according to FIG. 2.

FIG. 4 shows a schematic top view of a combing section of a spinning mill according to FIG. 1 with a further embodiment.

FIG. 5 shows a partial view according to FIG. 4 with a further embodiment.

FIG. 6 shows a schematic partial view of a top view of a combing section (FIG. 4) in the delivery zone of the preparatory machine.

FIG. 7 shows a side view X according to FIG. 6.

FIG. 8 shows a further embodiment according to FIG. 6 on an enlarged scale.

FIG. 1 shows a combing section of a spinning mill with a preparatory machine 1 on which lap rolls W (hereinafter referred to as wound laps) are produced. The preparatory machine 1 is provided with a feed table 2 to which rows of cans K11 and K12 are assigned. The slivers withdrawn from the cans are supplied to drafting arrangements (not shown) and drafted into nonwovens. The nonwovens are placed on top of one another on the feed table 2 and supplied jointly to a winding apparatus 4 (FIG. 2). Before the web 6 thus produced is supplied to the winding apparatus 4, it is guided through calender rollers (not shown in closer detail). The wound lap W produced in the winding apparatus 4 through lap rollers 7 and 8 is ejected backwardly by means of a needle 10. During this process the web 6 is severed, with the end E placing itself on the outer circumference of the wound lap. During the ejection process in the direction of the arrow, the wound lap W is transferred to a trough 15 of a conveyor belt 14 which is a part of a transverse conveying device 12.

The wound laps W which are placed on the conveyor belt 14 are displaced step-by-step in the direction of the arrow and combined into a group of wound laps WG. The cross conveyor 12 extends into the zone of movement of a displacement bridge 20 which is guided overhead on rails 21

and 22. The rails 21 and 22 rest on the floor on schematically shown beams T. As is indicated by a double arrow, the displacement bridge 20 can move along rails 21 and 22 in both directions and is driven by a drive source (not shown in closer detail) which on its part is controlled by a control apparatus which is schematically shown in FIG. 3.

Combing machines K1 to K5 are arranged in a row behind one another parallel to the cross conveyors 12, which combing machines are also driven over by the displacement bridge 20. The individual combing machines K1 to K5 are provided with swivellable troughs 24 on which rest a group of eight reserve wound laps RW on standby for follow-up to a working position AP.

As is shown in FIG. 2 in particular, the wound laps W are wound up on a tube H which is provided with clearance DL.

As is shown schematically in FIG. 2, a height-adjustable gripper beam 26 is attached to the displacement bridge 20, which gripper beam is provided with individual gripper arms 27 which can be swivelled into the clearance DL of tubes H 20 for receiving the wound laps.

The slivers which are produced in the individual combing heads (usually eight) of the combing machines are transferred in the direction of the arrow to a drafting arrangement (not shown) of the individual combing machine and joined 25 into a combed sliver which is deposited in schematically shown cans K. The cans K are ejected after filling and transferred by hand or a conveying device for further processing to downstream machines schematically shown in the direction of the arrow.

The placement of the combing machines to the preparatory machine 1 as shown in FIG. 1 can be obtained by respective requirements in the material supply and discharge. The choice of this placement leads to the consequence that the unwinding direction of the wound lap W as 30 ejected by the preparatory machine with respect to the downstream further conveyance to the combing machines K1 to K5 is present in the wrong direction. This is shown in particular in FIG. 2. The wound lap W which is ejected to trough 15 shows a clockwise unwinding direction, whereas the backup wound lap RW which rests on trough 24 requires an anti-clockwise unwinding direction. This is shown in particular in the illustration of the wound lap which is situated in the working position AP. It is therefore necessary that the wound laps W which are supplied by the preparatory machine 1 are rotated by 180° prior to being received by the displacement bridge 20. This occurs in a rotating station 30 which will be explained in closer detail by reference to FIGS. 2 and 3.

The rotating station 30 is provided with a frame 32 which 50 rests on the floor and is fastened there. A cylinder 33 is fastened to frame 32 whose piston rod 34 is fastened to a gearbox 36. A motor M is flange-mounted on the gearbox 36, which motor M drives a transmission stage (not shown in closer detail) within the gearbox casing 36. A drive element 55 of said gear stage is torsionally rigidly connected with a shaft 38 which is rotatably held in pipe 40. The pipe 40 is torsionally rigidly flange-mounted on the gearbox casing 36 and is guided in the vertical direction in the frame 32. Two receivers 41 and 42 which face in opposite directions are fastened to the lower end of shaft 38. The receivers 41 and 42 can be arranged as shafts which are provided with a non-slip layer for example so that the wound laps received from the respective receiver maintain their position during the rotation. The distance b from the middle axle DA of the 60 rotating station 30 to the face side of the wound lap W1 corresponds to half the distance a between the adjacent wound laps of a group of wound laps WG. The consequence

5

is that the wound lap **W1**, following the performed rotating process by 180° to the position as shown in the dot-dash line, is positioned in such a way that the distance **a** to the previously rotated wound lap **W4** is maintained.

As is shown schematically, the empty tubes **H** are conveyed back to the preparatory machine **1** on the inner strand of the conveyor belt **14**. A detailed description of this device is explained for example in DE-A1-197 20 545.3.

FIG. 4, wherein like reference characters indicate like parts as above, shows a further installation, with the wound laps **RW**, which are in reserve in the combing machines, are present offset by 90° to the wound lap **W** which is ejected from the preparatory machine **1** to a receiving trough **50**. This machine line-up can also be obtained by a respective arrangement of the machines which are upstream and downstream of this process stage. The same elements which were described in FIG. 1 are provided with the same reference numerals in FIG. 4 so that the same need not be explained any further.

Only two downstream combing machines **K1** and **K2** are shown in FIG. 4. In practice, however, at least six combing machines are downstream of a preparatory machine. To ensure that the unwinding direction of the wound laps is correctly provided to the combing machines, a vertical rotational shaft **52** is provided through which the trough **50** with the wound lap **W** is transferred by arm **54** to a transfer location **US** (shown with the broken line) by means of arm **54**. This swivelling movement is marked with a double arrow.

Once the place of deposit is free on the conveyor belt **14** of the downstream cross conveyor **12** which is opposite of the transfer place **US**, the wound lap **W** is transferred by way of a pin **56** (e.g. a cylinder) to the conveyor belt **14**. Stops (not shown) can be provided in the zone of the conveyor belt **14** on the cross conveyor **12** in order to limit the rolling path of the wound lap, so that it will come to lie securely on the conveyor belt.

In the present case a complete group of wound laps **WQ** is present on the cross conveyor **12** for transfer to the displacement bridge **20** and for transfer to a downstream combing machine which reports a demand for wound laps. Once the group of wound laps **WG** has been removed by the crane bridge **20**, the stepwise conveyance of the wound laps **W** supplied to the conveyor belt **14** for the purpose of the formation of a new group of wound laps **WG** can be continued, as was already explained above.

FIG. 5, wherein like reference characters indicate like parts as above, shows a partial sectional view of an installation. As in the example of FIG. 4 the wound laps are present in the combing machine **K1** . . . **K2** offset by 90° on the delivery trough **50** of the preparatory machine **1**. Furthermore, the combing machines are lined up offset by 180° as compared with the preceding example, so that the winding progress occurs on the downstream combing machines in the opposite direction. This means that the wound lap **W** must be turned by 90° and the unwinding direction must be turned by 180° as compared with the solution shown in FIG. 4.

For this purpose trough **50** is swivellable about a rotational shaft **58**, as is shown with the double arrow. Moreover, the unwinding direction is reversed. The transfer to the conveyor belt **14** of a downstream cross conveyor **12** is also performed in this case by means of a pin **56**, as has been explained in the preceding example.

FIG. 6, wherein like reference characters indicate like parts as above, shows a further embodiment, with the wound lap **W** which is ejected from the preparatory machine **1** being

6

supplied to a trough **50**. In contrast to the example of FIGS. 4 and 5, the trough **50** is immovably attached. A cross conveying device **12** is arranged parallel and adjacent to the trough **50**, with the device having a conveyor belt **14** in order to form a group of wound laps **WG** (as described above) for a downstream conveying system (not shown).

In the zone of the transfer between the trough **50** and the shown end of the cross conveyor **12**, a rotating station **60** is arranged which is shown in particular in the enlarged side view X of FIG. 7, wherein like reference characters indicate like parts as above.

The rotating station **60** consists of a frame **72** which rests on the floor. Guide rails **70** are attached to the upper end of the frame **72** on either side, which rails extend transversally to the conveying direction of the cross conveyor **12** and the direction of ejection of the preparatory machine.

Wheels **69** of a carriage **68** run in said guide rails **72**. The actual rotating apparatus for the wound laps is rotatably held in said carriage. Carriage **68** is associated with a displacement apparatus which is attached to the frame which is not shown for reasons of clarity of the illustration. The displacement apparatus could consist of a cylinder for example which acts on the one hand on the frame **72** and on the other hand on carriage **68** in order to perform the horizontal displacement as indicated with the double arrow.

The rotating apparatus consists of a cylinder **65** which is rotatably held (see double arrow) in the carriage **68**. The rotational movement of the cylinder **65** is performed by a schematically shown drive **66** which is fastened above the carriage. The cylinder is provided in the shown example with a piston rod **62** which is also designated as a rotating shaft about which the wound lap **W** is rotated.

A horizontally aligned receiver **63** is attached at the end of the rotational shaft **62**, which receiver projects in the shown example into the free space of the tube of the wound lap **W** resting on trough **60**.

As is shown in FIG. 6, sensors **S1** and **S2** are applied in the zone of the trough **50** and in the end zone of the cross conveyor **12** in order to monitor the presence of a wound lap **W** or **W'**.

FIG. 7 further shows a drive **75** which drives the deflection pulley **77** of belt **14** via the drive connection **76**. The deflection pulley **77** is held in the frame **78** which rests on the floor.

The drive **76** is controlled through the control unit **S** which also controls the preparatory machine **1** and the movements of the rotating apparatus **60**. The signals **S1** and **S2** are sent to the control unit **S** for evaluation.

Based on the position A (FIG. 6) of the rotational shaft **62**, the mode of operation of the apparatus is described below.

The control unit **S** is reported by sensors **S2** that no wound lap **W'** is located any more at the transfer location (shown with the broken line). The wound lap **W** is lifted by cylinder **65** by means of receiver **63** by a certain amount, so that it no longer rests on the trough **50**. Thereafter carriage **68**, and thus the receiver **63**, is displaced to position B by a displacement element (not shown). The rotation of the wound lap by 90° (see double arrow) occurs thereafter by means of the rotational drive **66** and the rotatably held cylinder **65**.

The wound lap is now lowered by means of cylinder **66** until the lap rests on the conveyor belt **14**. This is then reported by sensor **S2** to the control unit **S**. Once this process is completed, the control unit sends a signal to the drive **75** which puts in motion the deflection pulley **77** and thus the conveyor belt **14** in the direction of the arrow until the new wound lap has been displaced by a respective winding

division and sensor S2 reports again that the receiving place on the conveyor belt is once again free.

In order to monitor the precise winding movements on the conveyor belt there are further sensors (not shown).

During this displacement of the new wound lap via the conveyor belt, the receiver 63 has become free again, as a result of which the same is swivelled back in the opposite rotational direction. From this position (B) the receiver 63 can be displaced via carriage 68 to position A again once the sensor S1 reports that a new wound lap W is present on the 10 through 50. The described process can thus start anew again.

Once a complete group of wound laps WG is present on the cross conveyor 12 the group can be received by the conveying system (not shown).

The embodiment of FIG. 8, wherein like reference characters indicate like parts as above, corresponds substantially to that of FIG. 6, with only three further receivers 63a, 63b and 63c being fastened to the rotational shaft. This device allows omitting the additional reversing movement of the rotational shaft after the delivery of the wound lap W to the conveyor belt 14, as was necessary in the aforementioned apparatus according to FIG. 6. The other movement sequences are the same, so that they need not be described here again.

Once the wound lap W deposited on the conveyor belt 14 has been further conveyed by a winding division, the rotating apparatus can be displaced in this case (FIG. 5) without any further rotational movement in the direction towards position A in order to receive a new wound lap W there.

With the proposed apparatuses it is possible to provide a simple and flexible adjustment to the different line-ups of the machines in the spinning room, thus always ensuring the correct feed of the wound laps in the combing machines. This concept allows incorporating combing sections in existing plants without having to re-organize the entire machine outfit.

What is claimed is:

1. In combination,

a preparatory machine for sequentially delivering wound laps, each wound lap having a longitudinal axis and a

tube disposed in parallel to said common longitudinal axis;

a conveyor belt disposed parallel and adjacent to said preparatory machine for sequentially receiving the delivered wound laps;

first means for driving said conveyor belt in stepwise manner; and

second means located between said preparatory machine and said conveyor belt for sequentially rotating each wound lap 90° horizontally in a plane of said longitudinal axis thereof and conveying each wound lap from said preparatory machine onto said conveyor belt in coaxially equi-spaced apart relation, said second means including a vertically disposed rotatable shaft, at least one horizontally disposed receiver mounted on said shaft to engage within said tube of a wound lap, a drive for rotating said shaft to rotate an engaged lap on said one receiver 90° and a carriage having said shaft and said drive mounted thereon, said carriage being movable transversely of said conveyor belt to move an engaged lap on said one receiver from said preparatory machine to said conveyor belt.

2. The combination as set forth in claim 1 further comprising means for raising and lowering said shaft relative to said conveyor belt.

3. The combination as set forth in claim 1 wherein each said receiver has a non-slip surface to receive said tube of a wound lap thereon.

4. The combination as set forth in claim 1 wherein said second means has four of said receivers mounted thereon in equi-spaced angular region.

5. The combination as set forth in claim 1 wherein said first means includes a control device to drive said conveyor belt in stepwise manner to space the wound laps delivered onto said conveyor belt in equi-spaced relation along said conveyor belt on a common longitudinal axis.
